UNITED STATES PATENT OFFICE.

J. H. WITHEY, OF WINCHESTER, ILLINOIS.

IMPROVED SUGAR-EVAPORATOR.

Specification forming part of Letters Patent No. 38,710, dated May 26, 1863.

To all whom it may concern:

Be it known that I, J. H. WITHEY, of Winchester, in the county of Scott and State of Illinois, have invented a certain new and useful Improvement in Apparatus for the Manufacture of Sirup and Sugar from the Juice of Sorghum-Cane, of which the following is a full, clear, and exact description, reference being had to the accompanying Drawings of the same, making part of this specification, in which—

Figure 1 represents a plan of my improved apparatus, and Fig. 2 a vertical longitudinal section taken through the same at the line x x . Fig. 3 represents an end elevation of the same.

The object of this invention is to provide a simple and cheap yet effective apparatus for the production of sirup and sugar from the juice of the sorghum-cane, and which, from being little liable to get out of order, and capable of being easily managed, would commend itself for general use.

Previous to giving a special description of the various parts of the apparatus, it may be well to remark that while it is represented in the drawings as consisting of but a single set of pans or "teaches" for the completion of the process, yet it is also intended to be enlarged whenever desired, so as to be used with two sets to increase the capacity of its production. The apparatus, when comprised of a single set of pans, will consist of one defecating or skimming pan and two evaporating-pans, only one of the latter of which will be subjected to the influence of the furnace, however, at a time; and when consisting of two sets it will have one or two, as may be desired, defecating-pans and two sets of evaporating-pans. I will first describe the single set of apparatus.

The defecating-pan A is raised above the level of the evaporating-pans B and B, so that the clarified juice may be run off into them free, or nearly so as possible, from impurities or foreign matter other than those required for the perfection of the process; but as the invention consists in this instance in the apparatus, and not in the process of making sugar and sirup, I do not deem it necessary to particularize the latter or the ingredients used

in the defecation; &c., further than is necessary for a full illustration of the management of the apparatus.

The apparatus consists of two principal parts—the furnace and the boiling apparatus and appendages. The furnace for a single set of pans is constructed of brick or other suitable material, and about four times as long as it is broad, and the rear half raised about the width of a pan higher than the front end, and is provided with two fire-places or furnaces, the one, G, immediately below the defecating-pan A, and having its feed-aperture for wood and air, &c., on the side of the furnace, and the other, D, at the front end of the pan, immediately underneath the evaporating or concentrating pans B. The former C is merely intended to be used for the purification of the first pan of juice, which on its completion is then run off through the cock a into the evaporating-pan B, that is arranged over the front furnace, the fire in which is then kindled, it having previously been prepared for that purpose, and the other allowed to subside, in order to concentrate the juice by the evaporation of its aqueous particles into sirup or into sugar by a further continuance of the heat. While the concentration of the clarified juice in the evaporating-pan B is being carried on, the damper e is turned down, as represented in Fig. 2, to allow the waste heat of the furnace to pass under the defecating-pan A, in order to purify, by skimming, &c., the new charge of juice with which meanwhile it has been provided after running off the first, to be ready to charge the second evaporating-pan B, when the first has been sufficiently concentrated to be removed from the fire.

Should the defecation of the juice in the pan have been completed previous to the concentration of the sirup in the evaporating-pan B, then, unless you should elect to continue the evaporation of the charge in the pan A, the damper e is turned up to shut off the passage of the heat and smoke from the pan A and cause them to pass toward the chimney E, beneath the bottom plate, F, without acting on that pan, for which purpose openings h are formed in the bed-plate, which allow free passage to the smoke, &c., to the chimney. Should the heat from the front fur-

nade, D, however, be insufficient to perfect the purification of the raw juice in the pan, then the other furnace, C, may also be kindled and kept burning as long as may be deemed necessary; or, if deemed advisable, instead of kindling the fire underneath the defecating-pan A, both it and one of the evaporating-pans may be for the first charge filled with the raw juice and the front furnace kindled, defecating both and completing the concentration of the juice in the evaporating-pan; but such is rather objectionable, as it gums up the evaporating-pan B with matter which had better be avoided. In apparatus having but a single set of evaporators, the partition *c*, dampers *d* and *d'*, and chimney *G* (represented in the drawings) are not required, they having been placed there to illustrate the operation and management of the fires when two sets of evaporating-pans are used. When such are used, the end chimney, *E*, is removed and the furnace-walls extended to a length sufficient to accommodate another set of evaporating-pans like the two illustrated in the drawings, they being arranged, supported, and operated in precisely the same manner and as will shortly be described. With such the damper *e* is turned down, as before, so as to cause the heat and smoke to pass under the defecating-pan A and between the partition *c* and the wall of the furnace, whence it is deflected through the opening *m*, formed in the bottom plate, and thence under the other evaporating-pan, and again caused to descend through an opening cut in the farther end of the bottom plate for that purpose, also provided with a damper, and thence back and out of the chimney *G*, in which is formed an opening, *h*, for that purpose.

In the double apparatus, when it is only desired to use one set of evaporating-pans, then the damper *d'* is kept closed and the other damper, *d*, opened, so as to cause the heat and smoke, &c., to pass back under the defecating-pan and out through the opening *j* of the chimney *G* on the upper side of the bed-plate.

The handles *l* and *l'*, for operating the dampers *d* and *d'* in large apparatus, instead of being arranged as represented in the drawings, will be extended through the side of the furnace, that they may be operated from the outside.

Instead of using one large furnace for the heating of both sets of evaporating-pans in a large apparatus, each set may be heated by separate furnaces, if desired, one arranged at either end, and both provided with dampers *e*, to suffer the heat to pass under a large defecating-pan A, for the supply of both sets, in which case the partition *c* and dampers *d* *d'* could be dispensed with entirely, two dampers, *X* *X*, arranged one at either end of the defecating-pan A, like damper *e*, being all that would be necessary for the practical operation of the apparatus.

Each pair of evaporating-pans, as well for the single as the double apparatus, are connected together by means of a link, so that either may be inclined without affecting the level of the other. On the ends of one of each set are secured a notched bar, *i*, the teeth of which are made to engage with pinions *n*, mounted on a crank-shaft, *k*, supported and turning in bearings secured to the side of the furnace, by turning which one pan, on the completion of the concentration of the clarified juice, is removed from the fire, and the empty one brought over it, to be filled from the defecating-pan A with the juice prepared in it for that purpose, where it in turn is subjected to the action of the fire until sufficiently concentrated, and then removed like the other, and the empty one taking its place, as before, and so on until the whole has been prepared and completed. To facilitate the removal of the pans B in this manner, they are supported upon rollers *p*, mounted in frames made of iron, whose transverse section is like or similar to a U with the convex side turned downward. Each set of pans has two of these series of rollers and frames *r* arranged so as to support the pans at their ends. Each of the series of rollers has three distinct frames, *r*, the middle one bridging the walls of the furnace, and the other two arranged so as to form a prolongation of it—one on each side of the furnace. The outer ends of the exterior frames *r* are supported on and connected to the upper end of a strong rod, *s*, the lower end of which is attached to a crank-head, *s'*, mounted on a crank-shaft, *q*, which has its bearing in a hollow standard, *H* while the inner ends of the frames *r* are hinged to the outer end of the middle one, *r'*. By this arrangement the pans B may be so tilted as to throw the whole sirup toward one corner, into which is inserted a cock, *t*, and thus draw the whole off with very great facility. This is effected by turning the crank-shaft *q* of the standard *H* at that end of the pan farthest removed from the cock *t* so as to raise that end, and by turning the other so as to depress that end of the pan next the cock *t*. It will be seen by reference to the drawings that each pan B has its own set of rollers and adjustable frames, the one on the one side and the other on the other side of the furnace.

To prevent any tendency of the pans to move angularly across the furnace and frames, guide-bars *w* are secured to their under side in such manner as to embrace the two sets of rollers between them; but, if desired, depressions could be formed on their under side, within which the rollers can operate. To give stability and strength to the standards *H*, braces *I* are secured to them and to the walls of the furnace.

What I claim as new, and desire to secure by Letters Patent, is—

1. The arrangement and operation of the damper *e*, in connection with the defecating

and evaporating pans A and B, for the purposes set forth.

2. In combination with the evaporating-pans B, the arrangement of the adjustable roller-frames r , operating substantially as described, for the purposes set forth.

3. The arrangement and operation of the dampers d and d' , where two sets of evaporating-pans, B, are used, for the purposes set forth.

In testimony whereof I have hereunto signed my name before two subscribing witnesses.

J. H. WITHEY.
